UNITED STATES PATENT OFFICE.

GEORGE A. RAHMEYER AND FRANZ P. RAHMEYER, OF ANSLEY, NEBRASKA.

AUTOMATIC CARRIER.

1,405,718.

Specification of Letters Patent.

Patented Feb. 7, 1922.

Application filed May 6, 1920. Serial No. 379,342.

To all whom it may concern:

Be it known that we, GEORGE A. RAHMEYER and FRANZ P. RAHMEYER, citizens of the United States, residing at Ansley, in the county of Custer and State of Nebraska, have invented certain new and useful Improvements in Automatic Carriers, of which the following is a specification.

This invention relates to carriers, and the primary object of the invention is to provide an improved dumping carrier which can be effectively used for transporting litter, removing or placing ensilage in silos, placing food in animal troughs, or any other similar purpose.

Another object of the invention is to provide an improved overhead dumping carrier, which when dumped will automatically return to its normal position, thereby eliminating the labor and inconveniences generally associated with the closing of dumping carriers now on the market.

Another object of the invention is to provide an improved carrier box which can be readily dumped at any desired point and the contents of the carrier box dropped directly below the same, thereby insuring the unloading of the contents of the carrier at the correct place.

A further object of the invention is to provide an improved carrying box which can be effectively used either as a vertical hoist, or as a horizontal sliding carrier, the carrier having means to permit the same to be automatically dumped, when used as a horizontal carrier.

A further object of the invention is to provide an improved dumping carrier embodying a pair of pivoted sections, which are constructed exactly alike, and so connected that the same will move together and thereby permit the articles in the carrier to be dropped directly below the same.

A still further object of the invention is to provide an improved carrier box, of the above character which is durable and efficient in use, one that is simple and easy to manufacture, and one which can be placed upon the market at a reasonable cost.

With these and other objects in view, the invention consists in the novel construction, arrangement and formation of parts, as will be hereinafter more specifically described,

claimed and illustrated in the accompanying drawings, forming a part of this specification, in which drawings:

Figure 1 is a side elevation of the improved carrier box, showing the same slidably mounted on a supporting cable.

Figure 2 is an end elevation of the carrier when used as a hoist.

Figure 3 is a side elevation of the carrier when used as a hoist, showing the catches being released for permitting the sections of the carrier to move to their dumping positions, portions of the carriers being shown in section, and

Figure 4 is an end elevation of the carrier showing the same in a partly dumped position, parts of the carrier being shown in section.

Referring to the drawings in detail, wherein similar reference characters designate corresponding parts throughout the several views, the letter A generally indicates the improved carrier, and B, the supporting cable therefor which may be of the ordinary or any preferred construction and supported in any manner. The cable B may be provided at any desired point with a depending stop lug 5 as clearly shown in Figure 1 of the drawings, which forms means for automatically dumping the carrier A when the carrier A reaches a predetermined point on the cable.

The carrier A includes companion sections 6 and 7, which are constructed exactly alike with the exception that the section 6 is formed slightly shorter than the section 7 so as to permit the sliding of the same in the section 7 when the carrier is being dumped. Each of the sections 6 and 7 includes a longitudinally extending side wall 8, end walls 9 and a bottom wall 10 and when the sections 6 and 7 are in their operative positions in relation to each other, the same form a substantially rectangular shaped casing or box which can be used for transporting any desired material. The end walls 9 of each section 6 and 7 are preferably braced by angle irons 11, but these angle irons may be dispensed with if not found desirable or practical. The sections 6 and 7 may be further braced by diagonally extending bars 12, which extend from one terminal of the angle irons to the other.

A supporting structure 13 is provided for the sections 6 and 7, and this supporting structure includes a longitudinally extending centrally disposed beam 14', which has its terminals provided with downwardly and outwardly inclined arms 14 and 15, and these arms may be formed of angle iron if so desired and either made integral with the supporting beam 14' or separate therefrom. 5 The lower terminals of the arms 14 and 15 extend beyond the ends of the sections 6 and 7 and are secured as at 16 by means of suitable pivot pins to upwardly extending straps 17 which are bolted or otherwise secured to the end walls 9 of the sections 6 and 7. 10 These strap irons 17 are located adjacent to the side walls. The downwardly and outwardly depending arms 14 and 15 have secured to their upper ends the inwardly and downwardly extending stops 18 which are substantially U-shaped in cross section, and these stops 18 are located intermediate the arms 14 and 15 and form means for receiving the upper ends of the end bars 19 which 20 are bolted or otherwise secured to the end walls 9 of the section 7. These bars 19 as clearly shown in Figures 2 and 4 of the drawings are located flush with the outer edge of the end walls 9 of the sections 7 and 25 extend slightly beyond the upper edge of the same. These bars 19 prevent swinging movement of the sections 6 and 7 outwardly of the arms but permit the sections to be swung inwardly. The stops 18 are provided with openings 20 which register with openings 21 in the upper ends of the bars 19 when the sections 6 and 7 are in their operative carrying positions, and these registering openings are adapted to receive the outwardly extending teeth 22 formed on the 30 catches 23 which are pivotally supported as at 24 on lugs 25 carried by the outer edges of the longitudinally extending beam 14'. These catches are adapted to be operated by 35 means which will be hereinafter more fully described.

To insure that the sections 6 and 7 will operate synchronously a connecting bar 26 is provided, which pivotally connects the 40 end walls 9 of each section 6 and 7 together. The connecting bars 26 have their upper ends pivotally connected as at 27 to plates 28, which are secured to the upper edges of the side walls 9 of the section 6 intermediate its ends. The lower ends of the connecting bars 26 are pivoted as at 29 to face plates 30 which are secured to the inner edges of the end walls 9 of the section 7. Thus it will be seen that when one 45 of the sections is swung inwardly the other will be moved therewith. The dotted line position of this bar is clearly shown in Figure 2 of the drawings when the sections 6 and 7 are swung to their fully opened position.

It can be seen that when the carrier A is loaded the sections 6 and 7 will have a tendency to swing open owing to the weight of the contents acting on the lower walls 10 of the sections, and as soon as the catches 23 are released, these sections 6 and 7 will readily swing on the pivot pins 16 and permit the contents of the carrier to be dumped. 70

To insure that the sections 6 and 7 will return to their normal positions after the 75 contents of the carrier have been dumped, springs 31 are provided which are of the V-shaped type and are provided with intermediate coils 32 so as to permit the ready flexing of the springs when necessary. One 80 terminal of the springs is secured to the side walls 9 of the sections 6 and 7 while the other terminals are secured to the arms 14 and 15 of the supporting structure 13. These arms 14 and 15 may be connected together by a cross brace 33 if found necessary. 85

The carrier can be effectively used, as stated either for hoisting the material or for transporting material in a horizontal plane, and in Figure 1 the carrier is shown especially adapted for transporting material in a horizontal plane and in this figure the supporting beam 14' is provided adjacent to its terminal with upwardly extending

supporting brackets 34, which carry rollers 90 95 35 which are adapted to engage the supporting wire B. In this form the carrier is adapted to be automatically dumped and levers 36 and 37 are pivoted intermediate their ends to a longitudinally extending U-shaped bracing member 38 which is secured to the longitudinally extending supporting beam 14'. The levers 36 and 37 extend on the opposite sides of the transverse center

of the carrier and are connected together by 100 a rod 39 for synchronous movement. The lower terminals of the levers 36 and 37 have connected thereto flexible cables 41 and 42, which are crossed intermediate their ends. The cables have their opposite ends connected to the latches 23. The terminals of the U-shaped bracing member 38 carry depending lugs 43 which support pulleys 44 for supporting the cables 41 and 42. It can be seen that when the carrier is being moved 105 along the supporting cable B and one of the levers 36 or 37 hits against the depending stop 5, the catches will be operated, which will permit the sections 6 and 7 to be swung open. 110

In Figure 3 the carrier is shown as being used for hoisting articles and when used for this purpose the end brackets 34 may be dispensed with and the intermediate bracket 45 is used in lieu thereof which is bolted or otherwise secured to the longitudinally extending bracing member 38. The bracket 45 is located intermediate the levers 36 and 37 and it is provided with an eye 46 which is adapted to receive a hook or the like 115 120 125 130

mounted on a suitable hoisting cable 48. When used as a hoist, cables 49 and 50 are used in lieu of the cables 41 and 42 and these cables have their inner ends connected 5 directly to the lower terminals of the levers 36 and 37 and are extended straight to the latches 23 and are not crossed like the cables 41 and 42. These cables are also trained around the supporting pulleys 44 provided 10 for that purpose. A pulling rope or cable 51 may be secured to either one of the levers 36 and 37 and it can be seen that when a pull is exerted on the rope 51 the levers will be moved outwardly as clearly 15 shown in Figure 3 of the drawings which will effectively move the teeth 22 out of engagement with the registering openings formed in the stops 18 and the end bars 19.

In operation of the improved carrier, the 20 material to be transported is placed in the same, and the carrier is then moved along the cable B to the desired place and when one of the levers 36 or 37 comes into contact with the depending stop 5 the levers will be 25 swung on their pivots, thereby drawing the catches 23 from out of the registering openings 20 and 21 thereby permitting the rod 19 to move out of engagement with the stop 18. This permits the sections 6 and 7 to 30 swing on the pivots carried by the arms 14 and 15 and release the material therein. As soon as the material has been released, the sections 6 and 7 will immediately return to 35 their normal positions owing to the tension of the springs 31.

The form shown in Figure 3 is operated 40 exactly like the form shown in Figure 1 with the exception that when the carrier reaches the designated place where it is desired to drop the material contained therein the rope or cable 51 is pulled which will 45 operate the levers 36 and 37. The carrier illustrated in Figure 3 is especially adapted for removing or replacing ensilage in silos and considerably facilitates the handling of the ensilage.

From the foregoing description it can be seen that an improved carrier is provided 50 which is easy and simple to operate and will effectively dump the material contained therein at the desired place.

Changes in details may be made without departing from the spirit or scope of the invention; but,

55 We claim:

1. A carrier comprising a casing including a pair of companion sections, a supporting structure for the casing, means independently connecting the sections to the supporting 60 structure for swinging movement, a stop carried by the supporting structure, means connecting the sections together for synchronous movement, a rod carried by one of the sections arranged to engage said stop to limit the swinging movement of the sections in one direction in relation to the supporting structure, pivoted catches carried by the supporting structure and arranged to engage said stop and rod to normally hold the sections against swinging movement on 65 the supporting structure, and means for operating said catches.

2. A carrier comprising a casing including a pair of companion sections, a supporting structure for the casing including a longitudinally extending bar, outwardly extending depending arms formed on the terminals of the bar, means pivotally connecting the sections to the terminals of the arms, a stop carried by the supporting structure, a bar 70 carried by one of the sections arranged to engage said stop to limit the swinging movement of one of said sections in one direction, means connecting the sections together for synchronous movement, pivoted catches carried by the supporting structure and arranged to engage said stop and bar, and means for operating said catches.

3. A carrier comprising a casing including a pair of companion sections, a supporting 75 structure for the sections, means pivotally connecting the sections to the supporting structure for swinging movement, releasable means normally holding the sections against swinging movement on the supporting structure, and spring means arranged to normally hold the sections against swinging movement.

4. A carrier comprising a casing including a pair of companion sections, a supporting 80 structure for the sections, means pivotally connecting the sections to the supporting structure, releasable means normally holding the sections against swinging movement, and spring means connecting the sections 85 and the supporting structure for normally holding the sections in operative position in relation to each other.

5. A carrier comprising a casing including a pair of companion sections, a supporting 90 structure including a longitudinally extending beam arranged above the casing, depending arms formed on the terminals of the beam and arranged at the opposite ends of the casing, means pivotally connecting the 95 sections to the terminals of the arms, means connecting the sections together for synchronous movement, a stop carried by the supporting structure, a bar carried by one of the sections arranged to engage said stop 100 to limit the swinging movement of the sections in one direction, pivoted catches carried by the supporting structure and arranged to detachably engage said bar to normally hold the sections against swinging movement, 105 levers pivotally connected to said longitudinally extending beam, means operatively connecting the levers to the catches, means

connecting the levers together for synchronous movement, and means for operating one of the levers.

6. A carrier comprising a casing including 5 a pair of companion sections, a longitudinally extending beam arranged above the casing, outwardly and downwardly extending arms formed on the terminals of the beam and arranged on opposite sides of the 10 casing, means pivotally connecting the sections to the lower terminals of the arms for swinging movement, means connecting the sections together for synchronous movement,

a stop carried by the terminals of the beam, means carried by one of the sections arranged to engage the stop for preventing 15 swinging movement of the sections in one direction, releasable catches arranged to engage said means carried by the section to normally hold the sections against swinging 20 movement, means for operating the catches, an eye carried by the beam intermediate its ends, and roller carrying brackets carried by the terminals of the beam.

GEORGE A. RAHMEYER.
FRANZ P. RAHMEYER.
